SNOW SCRAPER FOR AUTOMOBILES
OR THE LIKE

Robert L. Schmoller, Waukesha, Wis.

Application August 20, 1953, Serial No. 26,528

Term of patent 14 years

(Cl. D9—6)

To all whom it may concern:

Be it known, that I, Robert L. Schmoller, a citizen of the United States, residing at Waukesha, in the county of Waukesha and State of Wisconsin, have invented a new, original, and ornamental Design for a Snow Scraper for Automobiles or the like, of which the following is a specification, reference being had to the accompanying drawing, forming a part hereof.

In the drawing Fig. 1 is a perspective view of a snow scraper for automobiles or the like, embodying my new design; and Fig. 2 is a perspective view looking principally at the opposite side of the scraper from that shown in Fig. 1, the handle being omitted.

I claim:

The ornamental design for a snow scraper for automobiles or the like, substantially as shown and described.
